[57] **ABSTRACT**

A simple, inexpensive hanger means for a directory that is readily adaptable for any type of installation and which provides fast and secure attachment of the directory comprises a backing support member having an end support means integral with each end thereof and generally upstanding therefrom, said end support means having a wire attachment means integral therewith and a spring wire adapted to be snapped into locking engagement with the wire attachment means. A slot in at least one of the end support means receives therethrough a pair of legs of a detachable hanger connector. Each of the legs has a notch thereon which securely locks the hanger connector in place when the legs are spread. The detachable hanger connector has various connection means thereon such as a swivel, wire hook, and lanyard.

HANGER HARDWARE FOR A DIRECTORY**BACKGROUND OF THE INVENTION**

This invention generally relates to a support hardware for hanging an article for use and more particularly concerns a new means of attaching and containing a directory within a protective cover.

Maintaining telephone and similar directories conveniently accessible for use is important to assure maximum utilization of facilities such as telephone booths. A loose directory invites pilferage. Prior art attempts to tie the directory down have included binder covers with wires attached to the center of the spine, however, this has been found to have the disadvantage that with a heavy directory or hard use, the directory would have a tendency to bend the wire until the directory fell out. When an attempt was made to secure the wire more firmly, it resulted in a wire configuration which was difficult to remove when the directory was to be changed.

Other methods of hanging directories suffer similar disadvantages. In addition, the prior art means of hanging the directories have required relatively long field installation times. Also, these various methods have required the stocking of a complete line of each of the various types of directory hanger hardware. In a large metropolitan area with a great number of different types of installations the required inventory is expensive and space consuming.

SUMMARY OF THE INVENTION

An economical, simple, and adaptable directory hanger means which overcomes the disadvantages of the prior art comprises, according to my invention, a flat plate-like backing support member having an integrally formed end support means at each end thereof. The end support means generally upstand from the plane of the backing support and have a wire attachment means integral therewith. A spring wire which is adapted to slip between the pages of the directory is sprung into locking engagement with the attachment means to hold the directory firmly against the backing support.

The spring wire has a loop means at each end thereof which loop engages a depending tab formed by a U-shaped hole in the end support means. The wire is bent in a general W-shaped configuration with the loop means on the free ends engaging the tab of the end support means so that the spring bears against the backing support in the area of the bottom leg intersections. The backing support may be integrally formed with a suitable cover means to protect the cover of the directory. This construction allows simple but yet secure attachment of the directory in the cover. Accordingly, replacement time of the directories is minimized.

Adaptability of this directory securing means to the many different methods of hanging directories, is allowed by an arrangement having a detachable hanger connector with a pair of readily spreadable legs received through a slot in one of the end support means. Attachment of the detachable hanger connector to the end support is effected by inserting a screw driver in a space between the legs and twisting it to spread the legs so they are wider than the slot. A very secure locking effect is obtained by providing a notch in the outer edge of each leg so that when they are spread the notch engages an end of the slot.

With this construction only a single directory cover or backer support is required with detachable hanger connectors being used to accommodate the various types of hanging conditions. This detachable hanger connector is readily secured in place in the field with a simple twist of the screwdriver. Moreover, the hanger connector itself may be adaptable to several different types of hanger situations. Thus, the hanger connector will accommodate the common swivel connection and in addition may be readily fitted to accommodate wire hooks and lanyards.

From the above description of the invention it will be understood that I have invented an efficient and economical hanger means for directories.

BRIEF DESCRIPTION OF THE DRAWINGS

Other objects, features and advantages of the invention will be readily apparent from the following description of certain preferred embodiments thereof, taken in conjunction with the accompanying drawings, although variations and modifications may be effected without departing from the spirit and scope of the novel concepts of the disclosure, and in which:

25 FIG. 1 is a schematic representation of a hanger backing member showing its position relative to a cover and a directory secured therein;

FIG. 2 is a perspective view of a detachable hanger connector;

30 FIG. 3 is a perspective view showing the detachable hanger connector of FIG. 2 in place on the backing member of FIG. 1 with a screwdriver head in position preparatory to spreading of the legs for securing of the hanger connector to the backing member;

35 FIG. 4 is a view of the device of FIG. 3 showing the legs spread;

FIG. 5 is a perspective view showing a detachable hanger connector having a wire hook connection means thereon; and

40 FIG. 6 is a perspective view of a detachable hanger connector having a lanyard connection therewith.

DESCRIPTION OF THE PREFERRED EMBODIMENTS

45 A hanger means for a directory according to my invention may be seen in FIG. 1 to comprise a backing support member generally indicated at 10 in position in a cover means generally indicated at 12 holding a directory 14 shown in dotted lines. The backing support member 10 includes a planar body member 18 which may be of an elongated rectangular configuration generally coextensive with the binding of a directory 14. A first end support means 20 is integrally formed at one end of the body means 18 and a second end support 22 is integrally formed at another opposite end of the body portion 18. The first and second end support means 20, 22 may be of a general V-shaped configuration each having a first planar portion 20a, 22a upstanding from the main body portion 18 at an angle thereto. Also, each has a second planar portion 20b, 22b respectively, bent downwardly from the upper edge of the first planar portion to form a rigid end support means. In practice I have found it advantageous to form the body portion 18 and the respective end support means 20, 22 of a single strip of sheet metal with only two bends forming each end support.

The first planar portion 20a has a U-shaped hole 24 therein forming what may be referred to as a depending tab 26. A similar structure not shown, is formed in the second end support means 22. A spring wire 30 bent, as shown, in a general W-shaped configuration has a loop configuration 32 at each end thereof which is of a size to encircle the tab 26 and form a secure connection therewith. The fact that the loop completely encircles the tooth or tab 26 on each of the end support means prevents the wire from slipping out and sliding off. The spring wire is installed by engaging one end with an end support means, sliding it between the pages of the directory, bending it against its resilient spring action and snapping it over the opposite end support tab. When the cover and directory are hung in the usual position which is an inversion of that shown in FIG. 1, the spring wire loop 32 is pulled more securely onto the tab 26 making it impossible to slip off. The bends of the spring wire 30, as shown for example, at 30a, 30b and 30c provide great rigidity to the wire and serve to hold the directory 14 securely in place by urging the back of the directory against the body portion 18 of the backing support member 10. The above construction is simple and economical in both manufacture and maintenance. It will be understood that the backing support member 10 may be connected to or integral with the cover 12. It is also noteworthy that when combined with the cover 12 there are no sharp edges or projections which could injure the user or the directory.

Adaptability of the backing support member 10 to various types of installations is facilitated by a detachable hanger connector generally indicated at 40 in FIG. 2. As shown, the hanger connector 40 may be formed of sheet metal in a generally L-shaped configuration with a pair of legs 42, 44 formed in a first side 40a thereof. The legs 42, 44 have a space 46 therein which is adapted to receive a suitable spreading means for attachment of the hanger connector 40 to the backing support member 10. Each of the legs 42, 44 has an outer edge 42a, 44a having a notch 42b, 44b therein at a point spaced from the end of the leg.

The first end support means 20 has a slot 50 therein which receives the detachable connector 40 therethrough. The slot 50 has an axis generally parallel to the plane of the portion 18 so that as shown in FIG. 3 the legs 42, 44 will be juxtaposed to the body portion 18. With an end support means constructed as shown in FIG. 1 the slot 50 will be adjacent the intersection of the first planar portion 20a with the body portion 18. In addition, a corresponding slot 52 will be formed in the second planar portion 20b in alignment with the slot 50 so that the leg portion of the detachable hanger connector 40 will lie against the body portion 18.

With the hanger connector 40 in position as shown in FIG. 3 a suitable spreader means such as a screwdriver 55 is inserted in the slot 46 and twisted to spread the legs 42, 44 as shown in FIG. 4 and engage the notches 42b, 44b with the ends of the slot 50. This interfitting of the notches with the ends of the slot securely locks the hanger connector in place and prevents detachment even under conditions of extreme misuse. Any withdrawal force on the connector 40 is transferred to the edges of the notches 42b, 44b so that the legs 42 and 44 must shear before withdrawal is possible. Moreover, withdrawal of the connector 40 may be easi-

ly effected by a workman understanding the construction and properly squeezing the legs 42, 44 together.

The detachable hanger connector 40 has a second portion 40b bent at an angle to the first portion 40a and containing a swivel connector 60 along the free edge thereof. In practice the hanger connector 40 may be made of a single strip-like piece of sheet metal suitably notched and bent to form the legs, first portion, second portion and swivel connector from a single piece of material. This produces an economical and very strong connector member that is very capable of withstanding the loads and stresses imposed thereon. Where the directory hanger installation calls for a swivel connection of the directory hanger to a support, the detachable hanger connector 40 will be used and installed as shown and explained in connection with FIGS. 3 and 4. Where a different means of connection of the directory hanger means must be made, the detachable hanger connector 40 may be adapted to such different conditions. Thus, as shown in FIG. 5 the hanger connector 40, may have an additional wire hook connector means 70 thereon. The connector means 70 may be permanently fixed to the hanger connector 40 as by welding, or, preferably, the connector hook 70 may have a threaded end and be secured to the connector 40 by nuts, not shown. With the latter construction it will be seen from FIG. 5 that an interior nut would be protected and perhaps locked against movement by the second planar portion 20b and the swivel connector means 60 when the connector 40 was locked in place.

Support of the directory hanger means by a lanyard is shown in FIG. 6 with a first end 80a of a lanyard 80 affixed to a support 82 and a second end 80b attached to the hanger connector 40. In this case the end 80b may be permanently attached to the hanger connector 40, or, preferably, may extend through a hole, not shown, in the second portion 40b of the connector and have a suitable end enlargement preventing removal. Again, the end enlargement or other connector means will be protected between the second planar portion 20b and the second portion 40b of the connector. In each case the connection provides secure attachment and discourages vandalism.

Although it is contemplated that the detachable connector hanger 40 will be attached to only one end of the backing support member 10 the second end support means 22 may be similarly equipped to receive the detachable hanger connector at very little additional cost. This provides the advantages that it allows fool-proof installation. From the above description of the invention it will be understood that I have provided a new directory hanger means which is simple and inexpensive in production, installation and maintenance. Thus, as heretofore explained, both the backing support member 10 and the connector hanger 40 may each be readily stamped and bent from a single piece of sheet metal. With the backing support member 10 separate or embodied in a cover 12 the connector hanger 40 is easily slipped through the slots 50, 52 to the point where notches 42b, 44b are adjacent the ends of the rectangular notch 50 and a screwdriver is placed in the slot 46 and twisted to spread the legs 42, 44 outwardly thereby bringing the notches 42b, 44b into engagement with the ends of the slot 50 as shown in FIG. 4. The hanger connector 40 may have suitable connection

means thereon such as the swivel connection 60, the wire hook connection 70 and the lanyard connection 80 so that with this simple connection means the directory hanger cover may be secured in place. Further installation of the directory 14 is also readily effected by placing the directory with its back binding against the body portion 18, slipping the spring wire 30 between the pages, flexing the spring wire 30 against its resilient bias and snapping the free loop means 32 over the tab 26. With the simple construction maintenance is reduced to a minimum in that the hanger means is resistant to user abuse as well as vandalism.

Although only one tab 26 is shown with one wire 30 it is contemplated that two, three or more tabs and wires similar to 26 and 30 may be provided in generally parallel relationship.

Although minor modifications might be suggested by those versed in the art, it should be understood that I wish to embody within the scope of the patent warranted thereon all such modifications as reasonably and properly come within the scope of my contribution to the art.

I claim:

1. A hanger means comprising a backing support member including a first end support means at one end thereof and a second end support means at a second end thereof, said first and second end support means upstanding from said backing support member, said end support means having a wire attachment means integral therewith, and a spring wire having a loop means at each end thereof, said spring wire loop means being adapted to be sprung into locking engagement with said wire attachment means, each of said wire attachment means being a U-shaped hole forming a depending tab, said loop means encircling said depending tab to lock said spring wire securely in place.

2. A hanger means according to claim 1 wherein said wire is bent in a general W-shaped configuration with said loop means being formed on the free ends thereof and said spring wire contacting the backing support member generally at the bottom leg intersections of said W-shape to bias said loop means onto said tabs.

3. A hanger means according to claim 1 wherein said first end support means has a slot therethrough, said slot having an axis generally parallel to a transverse axis

of said backing support member, a detachable hanger connector having a first portion thereof received in said slot.

4. A hanger means according to claim 3 wherein said first portion of said hanger connector includes a pair of legs, said pair of legs extending into said slot, said legs having a means for accommodating a spreader tool means for deformably spreading the legs beyond the width of the hole to lock it in position in said hole.

5. A hanger means according to claim 4 wherein said legs have a notch in an outer edge thereof, said notch engaging an end of said slot when said legs are spread.

6. A hanger means according to claim 3 wherein said detachable hanger connector has a swivel connection means thereon.

7. A hanger means according to claim 6 wherein said detachable hanger connector has an additional wire hook connection means thereon.

8. A hanger means according to claim 1 wherein at least one of said end support means has a generally rectangular slot therein, said slot being in said upstanding portion adjacent said body portion and between said U-shaped hole and said backing support member, said slot having its long axis generally parallel to the plane of said backing support member, a detachable hanger connector having a portion thereof received in said hole, said hanger connector including a pair of legs, said pair of legs being received in said slot, said legs lying on said backing support member in generally parallel juxtaposed relationship thereto.

9. A hanger means according to claim 1 wherein said first and second end support means are formed integrally with said backing support, said first and second end support means each having a first section bent upwardly from a generally planar main portion of said backing support and a second section bent downwardly whereby each of said end portions assumes a generally inverter V-shaped configuration.

10. A hanger means according to claim 9 wherein said first end support means includes slots in said first and second sections, said slots being aligned with each other and above said backing support, said slots receiving a detachable hanger connector therethrough, said hanger connector engaging said first section adjacent said slot therein whereby connection is effected.
